UNITED STATES PATENT OFFICE.

WILLIAM BERGER NELSON, OF CHICAGO, ILLINOIS, ASSIGNOR TO INTERSTATE IRON AND STEEL COMPANY, OF CHICAGO, ILLINOIS, A CORPORATION OF ILLINOIS.

COOLING BED.

Application filed March 25, 1922. Serial No. 546,574.

To all whom it may concern:

Be it known that I, WILLIAM BERGER NELSON, a citizen of the United States, residing at Chicago, in the county of Cook, State of Illinois, having invented certain new and useful Improvements in Cooling Beds, do hereby declare that the following is a full, clear, and exact description of the same.

10 My invention relates to cooling beds used in handling hot metal bars as they are delivered from the reducing-rolls of a rolling-mill, and consists in the novel and useful constructions herein described and then 15 pointed out in the appended claims.

In the accompanying drawings, which illustrate my invention and in which the same reference numerals indicate similar parts in the different views, Fig. 1 is a 20 top plan view of a longitudinal portion of a cooling bed of well-known construction and operation equipped with my invention, parts being broken away; Fig. 2 is a detail vertical sectional view on the line 2—2 in Fig. 1 with the guide in position when 25 no bars are passing it; Figs. 3 and 4 are similar views showing parts in various positions when bars are passing over the bed; Fig. 5 is a detail view, and Fig. 6 is 30 a detail view.

The object of my invention is to provide a new and useful guide for the bars as they pass from the inclined gravity section of the bed to the initial pocket of the 35 horizontal section, and of a type that is particularly adapted for use when the bed is handling flat stock in packs to permit the annealing on the bed of material of small cross-section, such as flat spring stock, which 40 would otherwise cool too fast on the bed to pass the required specifications unless it were annealed later.

Referring to the accompanying drawings which show my invention the reference letter A designates a long trough or run-out 45 table provided with a series of feed-rolls a which project through openings into the trough and convey the metal bar as it is delivered from the reducing-rolls. In practice the trough is usually long enough to 50 accommodate a 300 foot bar, and the cooling bed, of which only a section is shown, is correspondingly extended.

The skid-section B of the bed includes a 55 series of rigid inclined skid-beams B' upon

which the bars α are delivered from the trough. Between the beams B' are journaled in the bed a series of rocking-shafts C parallel with the beams and having arms C', C² and C³ extending therefrom; the 60 arms C' on the ends of the shafts are arranged to pass through open-end slots α' in the trough A so that upon oscillation of the shafts they will transfer the bar out of the trough to the bed, and the other arms 65 are arranged in staggered relation on opposite sides of each shaft and extend radially to project alternately into vertical position to form escapement stops or dogs above the skids as the shafts are oscillated, 70 the corresponding dogs of the shafts being arranged in a straight row extending longitudinally of the bed so that the hot metal bars α will be preserved in straight lines. Suitable mechanism which is well-known 75 and forms no part of my present invention, and so need not be here shown and described, actuates the rocking-shafts so that they are simultaneously rocked back and forth to allow the bars lying on the skids 80 to move by gravity successively down them from one row of dogs to the next lower row until they pass one by one from the last row upon the inclined guides B² at the lower end of the skid-section B by which they are 85 delivered to the front or leading pocket of the horizontal section of the cooling bed.

The rack-section of the cooling bed is composed of a series of parallel horizontal racks D arranged respectively in line with 90 the skid-beams as shown in Fig. 1. Each rack unit is composed of a base d and marginal vertical webs d' provided with a series of troughs or pockets D' which are V-shaped in cross-section, the corresponding 95 pockets of the racks being arranged in straight lines. Suitable mechanism of well-known construction, designated generally at D², will be employed to lift and move the bars from each pocket and deposit them in 100 the next one and discharge them upon the assembly-table (not shown), and when the bars are to be arranged in packs α' the inclined guides B² will be formed as jointed arms and the lower arms will be actuated 105 from below to oscillate to different positions in relation to the leading faces of the initial pockets as shown in Figs. 2 and 3 as now well-understood to form packing mechanism to deliver the bars from the skid- 110

section of the bed to the first row of pockets in the rack-section so that they will be disposed therein in a pack as shown at x' ; mechanisms for both these purposes are now well-known and form no part of my invention and so need not be here described in detail. The lower arms B^2 may be actuated by links B^3 pivoted thereto and to crank arms B^4 fixed on an operating shaft B^5 as shown in Fig. 6, the length of the stroke of the arms being controlled by the operator. The skid-beams and racks may have vertical ribs b , and d^2 , respectively arranged lengthwise in staggered relation.

15 A series of stock guides are disposed along the length of the rack-section, being spaced apart at suitable distances according to the length of the bars to be handled, and each guide being associated with one 20 of the racks D . Each guide consists of a substantially C-shaped curved arm E formed of a flat strip of spring-metal, about two (2) inches wide, and attached at its lower end to the frame d^4 of the rack-section of the bed below one of the racks. The base d of the corresponding rack is provided with an elongated slot d^5 extending longitudinally thereof between its webs, and through which the upper end of the associated guide extends. The upper end of each guide projects above the base to approximately the upper edges of the webs, and is inwardly curved and extended in a line tangential to the plane of the inner 35 or leading face of the first pocket of the associated rack; the end e of the guide is substantially in this plane and its tip e' is curved upwardly and outwardly to form a flared mouth between the guide and the leading face of the initial pocket as shown 40 in Fig. 2 when the bars are handled singly, and also between the guide and the top bar of a pack as shown in Fig. 3 when the bars are being accumulated in packs. By this 45 construction the guides are mounted and located below the racks, where they are out of the way, and their free ends extend through the racks to guide the bars while contacting with each bar only at their leading points.

50 When the bars move from the inclined section of the bed to the horizontal section they pass under the guides E which hold them from turning and ensure their uniform emplacement in the initial pocket of the racks. This feature is advantageous when the bars are handled singly as the guides prevent them from unevenly passing down the inner or leading faces of the first pockets 55 at different points in their length and so hold them against any twisting or deforming action that would then occur, especially in bars of considerable length. It is especially advantageous when the cooling bed is handling flat stock in packs as it prevents

the flat bars from turning and ensures their being seated with uniform motion so that all are properly positioned and alined in the pack; as shown at x' in Fig. 3 all the bars are guided edgewise into the pack. 70 When handling flat stock or bars, such for example as spring steel or other material of small cross-section, it is desirable to cool them in packs as this permits the annealing of the material while it is in the bed, and for successfully annealing the pack in the bed it is desirable to minimize the area of the contact of the bars with colder metal therein and so prevent the latter from drawing the heat from these portions of the bars faster 75 than the heat from the other portions of the pack can evenly anneal them. As the guides E are located between the webs of the racks these parts are out of line in the direction of the travel of the bars so that any portions of the bars that may be chilled by them are out of line and will be reheated to the temperature of the other parts of the pack by the exchange of heat by conduction from the large non-chilled portions to the small 80 chilled portion. As the guides seat the bars edgewise they are useful in packing or accumulating them in the first notch of the horizontal portion of the bed in an arrangement that secures uniformity in packing and permits the annealing of the material in the bed, and the tangential construction of the end of the guide so that it touches each bar only at its leading point and in a restricted area limited to a transverse line or edge 85 of the guide renders the chilling action of the guide itself negligible. 90

When the machine is handling either single bars or packs the transfer mechanism lifts and carries the material forward from pocket to pocket in the horizontal section of the bed and then discharges it upon a suitable assembly table (not shown), and as the material is carried out of the first pocket 100 it bends or flexes the guides rearwardly, their upper ends moving freely in their slots and their lips being moved into position slightly below the upper edges of the webs so that the material clears them in passing to the second pocket, the curvature 110 of the lips allowing the guides to easily wipe across a single bar or a top bar of a pack, as the case may be, without turning or disturbing its position. When the material clears the guides they spring back 115 into their normal position. 120

I claim:

1. In a cooling bed, an inclined skid-section, a horizontal rack-section having a series of pockets arranged in horizontal rows along its length, and a guide mounted below the initial pocket of each of a plurality of the racks and constructed to restrain the stock from turning as it passes from the skid-section to the rack-section. 130

2. In a cooling bed, an inclined skid, a horizontal rack having a base provided with an elongated slot, vertical webs on the base at the sides of the slot, and a movable guide secured at one end below the rack having its free end passing upwardly through the slot and terminating between the webs at the plane of the leading face of the initial pocket of the rack.
- 5 3. In a cooling bed, an inclined skid, a horizontal rack having a base provided with an elongated slot, vertical webs on the base at the sides of the slot and having a series of pockets, and a guide consisting of a flexible metal strip secured at one end below the rack and passing through the slot in its base and terminating below the tops of the webs, the free end of the guide extending tangentially toward the leading face of the initial pocket of the rack and 15 having its tip curved away from said face.
- 10

In testimony whereof I affix my signature.

WILLIAM BERGER NELSON.
